UNITED STATES PATENT OFFICE.

ULYSSES G. LEE, OF CHATTANOOGA, TENNESSEE. ASSIGNOR TO MONTAGUE MAILING MACHINERY CO., A CORPORATION OF TENNESSEE.

TYPOGRAPH.

1,051,240.

Specification of Letters Patent. Patented Jan. 21, 1913.

Application filed October 21, 1911. Serial No. 656,054.

To all whom it may concern:

Be it known that I, ULYSSES GRANT LEE, citizen of the United States, residing at Chattanooga, Tennessee, have invented certain new and useful Improvements in Typographs, of which the following is a specification.

The invention relates to typograph machines for embossing or impressing letters in metallic plates for use in addressing and mailing machinery.

One object of the invention is to provide an arrangement of punches, dies, and pressure mechanism therefor whereby the force exerted for making the impressions will be a compressive one in relation to the frame of the machine and parts carried thereby instead of a force tending to separate or tear the machine apart.

Other features of the invention will be clear from the following description, the invention consisting in the features herein-after described and particularly pointed out in the appended claims.

In the accompanying drawings Figure 1 is a central vertical sectional view through the machine embodying the invention; Fig. 2 is a plan view of the machine; Fig. 3 is a side elevation of the entire machine; Fig. 4 is a view of the cam shaft with the parts to be operated thereby; Fig. 5 is a detail view of the cam shaft alone; Fig. 6 is a side view of one of the compression levers; Fig. 7 is a plan view of said lever; Fig. 8 is a side view of a yoke forming part of the operating connection to one of the compression levers; Fig. 9 is a detail view of a cam operated lever for the carriage feed; Fig. 10 is a view of the guard for the hand lever by which the machine is operated.

In these drawings, 1 indicates a die carrier having two sets of dies 2, each set being arranged in an annular series and guided to move vertically through the carrier, each die having a projection or screw 3 bearing upon a plate 4 in turn mounted on springs 5 on the carrier so that any die may be operated independently of the other dies, the spring-supported plate 4 yielding for this purpose at the point where the operated die is located, the operated die being returned to its normal position by the spring plate. The carrier is mounted to rotate on a shaft or tube 6, the upper and lower ends of which are connected respectively with the main

base portion 7 of the frame and the overhanging bracket or upper portion of the frame 8. The carrier has thereon a gear wheel 9 meshing with a gear 10 on a shaft 11 which is driven through bevel gearing 12 from a knob or handle 13 on a shaft 14 suitably mounted in the frame. The shaft 11 has at its upper end a suitable indicator so that the operator, by bringing any desired letter on this indicator to a certain point, can make the corresponding dies register with upper and lower punches 15 and 16 mounted to slide vertically in the bracket 8 and in the base 7 of the frame, respectively. Each of these punches is held normally retracted by a spring 17. The upper punch is operated by a lever 18 having a bearing at 19 on the bracket, and having at its other end an adjustable screw threaded stud bearing on the upper end of the punch 15. At an intermediate point on this lever, and closer to the punch than to the bearing 19, connection is made pivotally with an operating rod 20 which extends down through the hollow shaft or tube 6, the lower end of this rod being pivotally connected with a yoke 21 which is operated by a cam A on the cam shaft a, suitable anti-friction bearings being interposed between the cam A and the yoke, as shown in Fig. 4. By this connection the compression lever 18 is operated to force the punch 15 downwardly, and thus to operate the die which is directly under this punch. The lower punch 16 is operated by a lever 22 which has its fulcrum on a roller 23 bearing up against the frame, as shown in Fig. 1, the intermediate portion of this lever being in engagement with cams B, B, on the shaft a, one of these cams being located on each side of the central cam A and the lever 22 being bifurcated, as shown in Fig. 7. The free end of this lever is provided with a socket having an anti-friction ball 24 therein, this ball bearing up against the lower end of the plunger 16. It will be observed that the point at which the force or pressure from the cam is applied to the lever 22 is nearer to the point of work than it is to the fulcrum 23, and this is also true of the upper lever 18.

It will now be seen that in the operation of the parts, when the punches 15 and 16 are forced toward each other to cause the dies to engage the plate to emboss the same,

the upper lever 18 is drawn down and the lower lever 22 is moved upwardly, and thus the pressure takes place in directions toward the center of the machine, and the strain is thus a compressive one instead of a separating one or one tending to tear the frame apart. In other words, the upper lever presses on a fulcrum and exerts its strain toward the center line of the machine, and the lower lever presses up against its fulcrum or toward the center line of the machine. Furthermore, it will be seen that the fulcrum of each lever is considerably removed from the point where the power is applied and the work done, which latter are close together and near the end of the lever opposite to the fulcrum, so that a comparatively small portion of the strain put upon the compression levers is transmitted to the frame of the machine. The lower lever has interposed between it and the cams B, B, an anti-friction bearing shown in Fig. 4. Because of the use of the cam for operating the lower lever, said lever must have a slight longitudinal motion of about one-sixteenth of an inch. This is taken care of by the anti-friction roller 23 before described, and by the anti-friction ball 24. The left hand ends of the lower lever are notched so as to retain the anti-friction roller in proper position. The yoke 21 also has slight movement under the action of the cam A, and to permit this it is pivoted to the lower end of the operating rod 20. The ball 24 rests upon an adjusting screw 25, and by this screw and the upper screw passing through the lever 18, the punches may be adjusted, and then the screws may be held by the jam nuts shown.

The centers of the two cams or eccentrics A, B, are located equidistant on opposite sides of the center of the cam shaft, and in line with the said center, so that the rotation of the cams or eccentric shaft in either direction causes the eccentrics to transmit opposite motions to their respective levers. The eccentric shaft has a movement of about one quarter of a revolution, and it is operated by a hand lever 26 at the right hand end of the machine. When the machine is at rest, the center of the larger eccentric A is in the same horizontal line with the center of the eccentric shaft, while the center of the smaller eccentric B, B, is in the same horizontal line, and in front of the center of the eccentric shaft, and thus when the eccentric shaft is rotated 90°, the center eccentric or cam A transmits a downward motion to the yoke 22, and at the same time the eccentrics B, B, transmit an upward motion to the lower lever 22, it being understood that the downward movement of the yoke 21 effects the downward movement of the upper lever 18. The mechanism for feeding the carrier for the blank is also operated from the cam or eccentric shaft a. The carrier presents the blank to the space in between the dies at X. This carrier is not shown in the present case, and may be of any suitable kind. It is operated through suitable connection with a gear wheel 27 on a shaft 28 mounted in the frame, the lower end of this shaft having fixed thereon a ratchet wheel 29 engaged by a pawl 30 pivoted to a pawl plate 31 which is mounted to turn about the shaft 28 and is operated through a link 32 from a lever 33 having a roller 34 acted on by the cam 35 on the cam or eccentric shaft a. A spring 36 attached to this lever and to a point on the frame of the machine gives the pawl its effective stroke, the action of the cam being to retract the pawl through the connections described. In this retracting action of the pawl it is moved back until the point thereof has passed one tooth of the ratchet wheel, and until it has almost reached the point of the second tooth. Then as the cam or eccentric shaft is being returned to its original position, the cam 35 moves away from the cam lever 33, and the spring 36, drawing upon the cam lever and link 32, moves the pawl in the opposite direction back toward its original position. When the point of the pawl reaches the tooth on the ratchet wheel that it passed during the first part of its motion, it picks up the tooth and rotates the shaft 28 one-fourteenth of a revolution, there being fourteen teeth in the ratchet wheel. Before the point of the pawl has engaged the tooth on the ratchet wheel to turn the shaft 28 and thus operate the carriage, the dies have returned far enough toward their original positions so that the plate then in the carriage is entirely free to be fed along for receiving the next impression.

It is sometimes desirable to move the carriage one space without embossing a letter. This is accomplished by moving the hand lever 26 one-half stroke, and for this purpose the guard 38 is provided with an indicator so that the operator may determine the amount of movement necessary to move the lever for giving a spacing movement to the carriage without operating the dies. In other words, moving the eccentric or cam shaft only about 45° and releasing it, the pawl will then engage the ratchet tooth before the embossing operation has proceeded to the point where the dies engage the plate, and on the release and return of said shaft the ratchet and consequently the carriage will be moved for one feeding action, and this movement will be the same distance as if the embossing operation had taken place.

By reversing the position of the eccentric or cams A and B by rotating the shaft 180° before mounting the spacing cam, the

movement of the hand lever may take place in the reverse direction from that shown in the present arrangement.

It will be observed from Fig. 1 that a circular row of teeth is provided on the under side of the die carrier, and these are engaged by a detent roller α' mounted in a cup or frame b and pressed upwardly by a spring e to engage the teeth. This roller acts to accurately align the die carrier.

I claim as my invention:

1. In combination in a typograph machine, dies, a carrier therefor, punches operating toward each other for moving the dies to make the impression, a lever for each punch, a frame on which the levers are fulcrumed, and means for applying pressure to the said levers at points intermediate of the fulcrum and punches, said levers being drawn toward each other for operating the said punches to thereby exert a compressive strain, substantially as described.

2. In combination in a typograph machine, dies, a carrier therefor, a pair of punches operating on opposite sides of the carrier and toward each other, an upper lever fulcrumed on the frame at one end and having its other end connected with the upper punch, a lower lever fulcrumed in the frame and having its opposite end connected with the lower punch, and means connected with the intermediate portions of the said levers but nearer the punches than the fulcrums for operating the said levers toward each other in the embossing action to thereby exert a minimum compressive strain on the machine, substantially as described.

3. In combination in a typograph machine, a carrier, dies thereon, punches on opposite sides of the die carrier, a pair of levers one for each punch, an eccentric carrying shaft in line with the center of the die carrier, a rod passing through the center of the die carrier and connected to one of the levers, a yoke pivoted on the said rod and engaged by an eccentric on the shaft, the other lever being engaged by an eccentric on the shaft, the said levers being moved toward each other and toward the center line of the frame in operating the punches to make the impression, the said last mentioned lever having a shifting fulcrum and a shifting connection with its punch, substantially as described.

4. In combination the frame, a die carrier, a hollow shaft carrying the die carrier, an upper and a lower punch, an upper lever having a fulcrum at one end on the frame and at its other end connected with the punch, an operating rod connected with the intermediate part of said lever, and extending through the center of the die carrier, an eccentric carrying shaft, an eccentric there-

on for operating the said rod, a lower lever, an anti-friction roll interposed between the said lower lever and the frame acting as a shifting fulcrum therefor, and an anti-friction ball between the other end of the said lever and its punch, and an eccentric on the shaft engaging the intermediate portion of the said lever, substantially as described.

5. In combination a frame, a die carrier mounted therein, an upper and a lower punch, upper and lower levers for operating the punch, a rod extending through the center of the die carrier, an eccentric carrying shaft in line with the said rod and having an eccentric thereon for operating the rod, and an eccentric on the shaft for operating the lower lever, said eccentric being disposed to draw the center rod downwardly and move the lower lever upwardly when the shaft is turned, substantially as described.

6. In combination in a typograph machine, a rotary carrier, dies thereon, punches on opposite sides of the die carrier, a pair of levers, one for each punch, a rod passing axially through the die carrier and connected to one lever between its fulcrum and the punch, and operating means to draw upon the said rod and also to draw upon the other lever at a point between its fulcrum and its punch, causing said levers to exert a compressive strain on the frame in operating the punches, substantially as described.

7. In combination in a typograph machine, a die carrier, punches, carriage feed mechanism, a single hand lever, a shaft operated thereby, eccentrics on the shaft, connections from the eccentrics on the shaft for operating the die punches, a connection from one of the eccentrics on the shaft for operating the carriage feed mechanism, said connection including a lost motion device for permitting the dies to be operated when the handle is moved a full stroke, and causing the feed carriage to be operated on the return stroke or for causing the operation of the carriage feed mechanism alone when the lever is operated a partial stroke, substantially as described.

8. In combination embossing dies, an eccentric shaft, connections from said shaft to the embossing dies, a carriage feed mechanism including a pawl and ratchet, an eccentric on the shaft with a connection for operating the pawl, a hand lever connected to the eccentric shaft operating the same on one movement to actuate the dies and to retract the pawl in excess of its movement necessary to engage a fresh tooth in the ratchet for the feeding operation, said pawl on the return movement of the handle operating the ratchet, said ratchet being also operated independently of the dies by giving the hand lever a partial movement in a forward direction and then a return movement, substantially as described.

9. In combination in a typograph machine, a die carrier, punches and the carriage feed mechanism, a single-hand lever, a shaft operated thereby, eccentrics on the shaft, connections from the eccentrics on the shaft operating the punches, a pawl and ratchet connected with the carriage feed mechanism, a spring for giving the pawl its effective stroke, a connection from the pawl to one of the eccentrics to retract the pawl, such retracting movement being in excess of that necessary to make the pawl engage a new tooth, and taking place when the hand lever is moved a full stroke to operate the dies, whereby the carriage feed mechanism may be operated by a partial stroke of the hand lever one way and return stroke without operating the die mechanism, substantially as described.

10. In combination with a frame, a die carrier mounted therein, dies on said carrier, punches mounted in the frame for operating the dies, a pair of levers one above and the other below the frame for operating the punches, and operating means connected with the levers at a point between the punches and the fulcrums of the levers, drawing the levers toward each other for operating the punches, the said levers bearing loosely on their fulcrums, substantially as described.

In testimony whereof I affix my signature in presence of two witnesses.

ULYSSES G. LEE.
